(57) **CLAIM**

The ornamental design for a bottle content transfer apparatus, as shown and described.

DESCRIPTION

FIG. 1 is a front plan view of the bottle content transfer apparatus of the present invention;

FIG. 2 is a rear plan view of the bottle content transfer apparatus of FIG. 1;

FIG. 3 is a right side plan view of the bottle content transfer apparatus of FIG. 1;

FIG. 4 is a left side plan view of the bottle content transfer apparatus of FIG. 1;

FIG. 5 is a top plan view of the bottle content transfer apparatus of FIG. 1; and,

FIG. 6 is a bottom plan view of the bottle content transfer apparatus of FIG. 1.

The broken lines are for illustrative purposes only and form no part of the claimed design.
